(57) **CLAIM**

The ornamental design for a compressor as shown and described.

DESCRIPTION

FIG. 1 is a perspective view of a compressor according to the new design.

FIG. 2 is a right-side view thereof.

FIG. 3 is a left-side view thereof.

FIG. 4 is a front view thereof.

FIG. 5 is rear view thereof.

FIG. 6 is a top view thereof; and,

FIG. 7 is a bottom view thereof.

In these drawings, the solid lines illustrate the claimed ornamental design, whereas broken lines, if present, illustrate unclaimed subject matter and form no part of the claimed design. The break lines in FIGS. 1 and 4-7 represent indeterminate length of the compressor, and form no part of the claimed design.
